UNITED STATES PATENT OFFICE

2,570,860

BACKBOARD AND HOOP TOY

Charles S. Redding, Louisville, Ky.

Application June 13, 1949, Serial No. 98,791

1 Claim. (Cl. 273—98)

1

This invention relates to a toy for simulating the game of basketball.

The object of this invention is to provide a toy in which a ball may be banked on a backboard and through a hoop similar to the way a regular basketball is banked through the basket.

A further object of this invention is to provide such a toy in small form so that it may be operated by a small child or any other person, at the same time retaining the principle of banking the ball through the hoop in the same manner as in the game of basketball.

A still further object of this invention is to provide such a toy in which after the ball is banked through the hoop once the operation may be repeated without having to lift the ball back through the hoop and without tangling the string.

In accordance with the present invention, the toy comprises a miniature backboard with a handle for holding it, a hoop attached to the backboard and a captive ball.

The invention will be described in greater detail in connection with the accompanying drawings illustrating a preferred embodiment of the invention and wherein:

Figure 1 is a perspective view of the complete toy,

Figure 2 is an enlarged detail of the hoop, likewise in perspective.

Referring to the drawings, the toy comprises a backboard 1 made of wood, plastic or similar material, substantially square in shape, having a handle 2 securely attached to the backboard by any normal fastening device such as a screw or rivet 13. If it is so desired, the handle may be shaped from the same piece as the backboard. A ball 7 made of rubber, plastic or similar resilient material is attached to the backboard by a string 5 attached to a small nail or tack 6. This nail or tack 6 is preferably attached at one corner of the backboard so that the string will not interfere with the operation of the toy by coming between the ball and the backboard and deflecting its bounce. The ball may be a plain round ball or it may be marked by moulding or painting with simulated stitches 4 to resemble a basketball. Attached to the front or playing surface of the board is a hoop 3, the plane of the hoop being perpendicular to the backboard as shown in Figure 1, and the rim of the hoop being spaced outwardly from the backboard by means of a leg 9. The hoop is attached to the backboard and held securely in position, so that it will not rotate or bend, by means of staples 12. A portion of the leg 8 bent at an angle to the other portion of the leg 9 of the hoop provides a

2

secure means of attachment. The staples 12 also aid in attaching the handle 2 to the backboard 1.

This hoop may be made from one single piece of wire as is clearly shown in Figure 2. An important feature of the toy is the gap 11 in the hoop 3. After the ball 7 has been dropped or banked through the hoop, the string 5 is disentangled from the hoop 3 by tilting the toy forward and letting the weight of the ball pull the string free through the gap 11. This prevents tangling the string about the hoop or making it necessary to retrieve the ball through the hoop after each successful play.

15 In operation, the handle 2 is grasped in one hand and by a forward and upward rotary motion the ball 4 is caused to swing in an arc at the end of the string 5. Near the upper end of the rotary sweeping motion, the hand is thrown back thus throwing the ball toward the backboard 1. The object is to cause the ball to strike the backboard slightly above the hoop 3 and at such an angle that it will bounce or bank downward through the hoop, thus making a score.

20 It is understood that although I have shown a preferred embodiment of my invention certain modifications may be made therein without departing from the spirit of the invention.

25 I claim as my invention:

30 A toy of the type comprising a paddle, a hoop and a captive ball, wherein: the paddle has a lower handle portion and an upper rectangular, imperforate portion without obstructions except 35 the hoop; the hoop is formed with a gap in its periphery to permit a string to pass through, and is attached to the paddle so that it is perpendicular to and below the center of the rectangular portion; and the ball is attached to one 40 corner of the rectangular portion of the paddle.

CHARLES S. REDDING.
